His Attorney.

UNITED STATES PATENT OFFICE

2,486,701

OVEN STRUCTURE

Leo F. Berg, Oak Park, Ill., assignor to Hotpoint
Inc., a corporation of New York

Application November 7, 1945, Serial No. 627,249

3 Claims. (Cl. 126—19)

1

This invention relates to oven structures, more particularly to those employed in domestic ranges, and it has for its object the provision of an improved oven structure of this character in which the oven lining is removable for replacement or repair.

At times, it is desirable to remove the oven lining for repair or replacement. Heretofore, in most oven structures to do this it has been necessary to move the range away from the wall to gain access to the fastening means detachably holding the oven lining in its operative position. This invention contemplates an improved oven structure arranged so that the lining can be removed from and replaced in the range without in any way moving the range. More specifically, it contemplates such a structure wherein the oven lining may be serviced from the front.

For a more complete understanding of this invention, reference should be had to the accompanying drawing in which Fig. 1 is a side elevation of an electric range having an oven structure embodying this invention, parts being broken away so as to illustrate certain details of construction; Fig. 2 is a fragmentary view of a part of the oven structure shown in Fig. 1, Fig. 2 being drawn to a larger scale than Fig. 1; Fig. 3 is a horizontal sectional view illustrating certain of the elements of Fig. 2 in plan; and Fig. 4 is a view similar to Fig. 2 but illustrating a modified form of this invention.

Referring more particularly to Figs. 1-3 inclusive, this invention has been shown as applied to an electric range 1. This range is provided with walls defining an outer cabinet 2; as shown, this cabinet is provided with a top wall 3, a rear wall 4, a front wall 5 and side walls 6 and 7. The front wall 5 is provided with an opening 8. Insertable through this front opening is an oven lining 9 which is provided with a rear wall 10, a bottom wall 11, a top wall 12 and opposed side walls 13. The oven lining 9 also is provided with a front opening 14 which when the lining is in its operative position lies in substantially the plane of the opening 8.

Also, when the oven lining 9 is in its operative position its rear wall 10 is positioned forwardly of the rear wall 4 of the cabinet so as to leave a space 15 between them. Mounted within the space 15 are a plurality of spaced-apart supporting brackets 16; in the specific embodiment of the invention illustrated two supporting brackets 16 are employed, one for each lower rear corner of the lining. Each bracket 16 has roughly the shape of a U, the two legs 17 and

2

18 being secured at their ends to the rear wall 4. For this purpose, the leg 17 at its outer end is provided with a pair of upright arms 19 bent upwardly at right angles to the leg, as shown, and these arms are formed with rearwardly offset sections 20 which are inserted through openings 21 provided for them in the rear wall 4 in order to secure the leg 17 to the rear wall, as shown. The end 22 of the other leg 18 extends downwardly at an angle to the leg, as shown, and this section is secured to the rear wall 4 by means of a screw fastening device 23.

The nexus 24 of each U-shaped bracket is provided with an outwardly extending ledge 25 upon which the oven lining rests, as shown. The nexus 24 also is provided with an outwardly extending tongue 26 spaced above the seat 25. This tongue, as shown, is lanced outwardly from the material forming the nexus. The seat 25 and the tongue 26 form a slot 27 between them, and received in this slot 27 is a projection 28 provided at the rear lower edge of the oven lining. As shown, the projection 28 is formed by extending the bottom wall 11 outwardly beyond the rear wall 10, and by folding the lower end of this rear wall about it as shown in Fig. 2.

It will be understood that when the oven lining 9 is inserted through the front opening 8 of the cabinet, the projection 28 is received in the spaces 27 in the two brackets 16 and that when it is so received the rear end of the oven is supported and also it is prevented from moving upwardly and downwardly within the cabinet.

The oven lining 9 is further secured to the brackets 16 by means of a pair of screw fastening devices 29 which are inserted through openings 30 provided for them in the rear wall 10 of the lining and which are received in threaded engagement in tapped holes 31 provided for them in the nexus 24 of the brackets. Preferably, each screw will be provided with a reduced lead-in section 32 to assist in "picking up" its tapped hole 31.

The screws 29 are further provided with a slotted head 33, or a hexagonal head, for convenience in screwing them in and out of their tapped holes. As shown in Fig. 2, the screw heads 33 abut the rear liner wall around its screw openings, whereby, when the screws are threaded into the brackets 16 to draw the liner toward the brackets, the heads close the screw openings.

It will be observed that the screw heads 33 are accessible from the interior of the oven. Therefore, to remove the oven lining, it is merely neces-

sary to remove the two screws 29 and pull the oven lining forwardly from the brackets. To assemble the oven lining with the brackets, it is merely necessary to insert the lining rearwardly into the cabinet so that the projections 28 are received in the slots 27 and then thread in the two screws 29.

At the front the oven lining is supported by a flange 34 turned inwardly from the front wall 5 of the cabinet about its front opening 8.

In the form of the invention shown in Fig. 4, the oven lining 35 is provided with integral rear and bottom walls 36 and 37 joined by a rounded corner 38. Here, the projection 39 for the oven which is seated upon the supporting brackets 40 is formed by a separate piece 41. As shown, this piece has a leg 42 secured to the rear wall 36 of the lining, a leg 43 secured to the bottom wall 37 of the lining, and a rearwardly projecting folded section 44 joining the two legs 42 and 43, as shown. Otherwise the supporting structure for this embodiment of the invention is the same as that shown in Figs. 1-3.

Preferably and as shown, the rear walls of the outer cabinet will be provided with stiffening ribs 45 (Figs. 1 to 3), 46 (Fig. 4) adjacent the points of attachment of the bracket legs with the wall, these ribs functioning to reinforce and strengthen the wall at the points of attachment.

While I have shown and described particular embodiments of my invention, it will be obvious to those skilled in the art that various changes and modifications may be made without departing from my invention in its broader aspects and I therefore aim in the appended claims to cover all such changes and modifications as fall within the true spirit and scope of my invention.

What I claim as new and desire to secure by Letters Patent of the United States is:

1. An oven structure comprising walls forming a cabinet having a rear wall and a front opening, walls forming an oven lining having a rear wall and a front opening, said lining being insertable as a unitary structure into said cabinet through its said front opening and from which it may be withdrawn, a substantially U-shaped bracket in said cabinet having its legs attached to the rear wall thereof and a nexus projecting forwardly therefrom into said cabinet and positioned adjacent to and spaced from the rear wall of said lining, a forwardly projecting ledge on said nexus coacting with a rearwardly extending projection on said lining to support said lining at the rear, and a screw inserted through an opening provided for it in the rear wall of said lining and threaded into said nexus, said screw being accessible through said front opening of said lining.

2. An oven structure comprising walls forming a cabinet having a rear wall and a front opening, walls forming an oven lining having a rear wall and a front opening, said lining being inserted as a unitary structure into said cabinet through its said front opening and from which it may be withdrawn, a substantially U-shaped bracket in said cabinet having its legs attached to the rear

wall thereof and a nexus projecting forwardly into said cabinet and positioned adjacent to and spaced from the rear wall of said lining, a forwardly projecting ledge on said nexus coacting with a rearwardly extending projection on said lining to support said lining at the rear, a second projection on said nexus spaced above said ledge coacting with said lining projection so as to prevent vertical motion of said lining at the rear, and a fastening element inserted through the rear wall of said lining readily detachably interconnected with said bracket so as to fasten said lining to said bracket, said element being accessible for attachment to the bracket and removal therefrom through the front opening of said lining.

3. An oven structure comprising walls forming a cabinet having a rear wall and a front opening, walls forming an oven lining having a rear wall and a front opening, said lining being insertable as a unitary structure into said cabinet through its said front opening and from which it may be withdrawn, a bracket attached to the rear wall of said cabinet projecting forwardly therefrom and having a supporting ledge, a projection on said oven lining extending from the rear thereof arranged to rest on said ledge so as to support said lining at the rear, said bracket also having a wall rising from said ledge and spaced both from said rear lining wall and the rear wall of said cabinet, and a fastening element inserted through an opening provided for it in the lining rear wall and readily attachable with said bracket wall so as to secure said lining to said bracket, said fastening element being accessible through the front opening of said lining and having a part thereof bearing against the surface of said lining wall around said opening to close it.
